UNITED STATES PATENT OFFICE.

THEODORE A. B. PUTNAM, OF NEW YORK, N. Y.

ELECTRIC RAILROAD-SIGNALS.

SPECIFICATION forming part of Letters Patent No. 229,009, dated June 22, 1880.

Application filed August 21, 1878.

To all whom it may concern:

Be it known that I, THEODORE A. B. PUTNAM, of New York, N. Y., have invented an Improvement on a certain patent granted to me September 19, 1876, numbered 182,384, for Electro-Magnetic Railway-Signals, of which the following is a specification.

The nature of my improvement consists of a new mode of depressing a lever operated by the wheel of a locomotive.

Figure 1 is a view of the lever complete. Fig. 2 is an end view of the action of the same. Fig. 3 is a side view of the same.

My invention consists of two lever-arms, A A, of suitable size and strength, placed suitably parallel with the rails to receive the impact of a locomotive-wheel and in contact end to end. The two arms A A are pivoted together at their point of contact to one end of a vertical bar, B, the whole forming a double lever of the third kind operated from either end to depress the bar B for the purpose of further mechanical movements.

The bar B is placed in guides so as to have a rising-and-falling movement, bearing on a lever-arm, as F, Fig. 3, Sheet 1, Patent No. 182,384, and Fig. 2 of annexed drawings, operating the mechanism required. The freeends of A A are confined by a pin working in a slot made in A A. Suitable guides c c are placed on each side of the levers A A, also serving

to prevent accumulations of gravel or snow underneath the same.

By suitably-placed rubber springs a a the normal condition of A A and B when pivoted together is more elevated in the center, sloping toward the two free ends of A A.

When the wheel of a locomotive enters upon A the two levers are simultaneously depressed and so kept during the period of time the wheel is passing over their entire lengths, the result being to keep formation E, Fig. 3, Sheet 1, Patent No. 182,384, and Fig. 2 of annexed drawings, raised for electrical contact for the same period of time.

I also claim the privilege of operating levers by a locomotive-wheel impacting on a rail bent vertically upward, the pressure of the wheel bearing such rail to a straight line precisely as the two arms A A, herein described, operate, and of which the bent rail is substantially only another form.

I claim—

The two lever-arms A A, constructed substantially as described, in combination with the bar B, guides c, and springs a, for the purposes as herein described and set forth.

THEODORE A. B. PUTNAM.
